BEVERAGE COOLING CABINET OF DRY
AIR TYPE

Louis Weiss, St. Louis, Mo.

Application June 2, 1947; Serial No. 751,651

12 Claims. (Cl. 62—102).

This invention relates to improvements in beverage cooling cabinets of dry air type, and more particularly to so-called bottle coolers, such as dispensing cabinets, from which cooled bottled products may be served to the consuming trade, and in which the bottles are cooled by a stream of air, in distinction from many of the types of coolers in which the bottles are submerged or otherwise cooled by direct contact with a chilling liquid.

The present developments pertain to dry coolers, in view of the recognized disadvantages of utilization of so-called wet bottle coolers or those in which the bottles are chilled by liquid immersion. Heretofore, in the dry type of bottle coolers generally available to the trade, many difficulties have been experienced, particularly in a marked inequality of cooling rates in different portions of the enclosure or cabinet. Furthermore, in many commercial types of structure for this purpose, it has been difficult properly to chill the bottles of beverage relatively freshly introduced to the cabinet. In certain types this difficulty has been overcome in some degree, but only by necessitating withdrawal for service those bottles which are difficultly or remotely accessible to the operator. Further prevailing difficulties include, incident to various attempts at quick chilling of air flow, a low temperature cooling coil, and frequent defrosting requirements, requiring frequent out-of-service periods. It is, accordingly, a major objective of the invention to overcome each of the difficulties noted, and to attain a design of bottle-serving cabinet in which the most accessible bottles are thoroughly chilled and in which, in a compartmented structure, all of the bottles in the several compartments are virtually uniformly cooled.

A further and important objective of the invention is attained in an organization for the purpose noted, in which is contained a novel arrangement of air-circulating and air-flow control elements, such as to conduce to substantial uniformity of bottle cooling in the several bottle containing regions of the cabinet.

An additional major object is attained in a novel arrangement of cooling coil, utilized in the present example, to cool a stream of air, with the latter in turn, cooling the bottles in the several bottle compartments.

A further objective is realized in a novel form of cooling unit in which a number of turns of tubing are so formed and assembled as to provide a zig-zag or somewhat sinuous course of air flow through the passes or turns of the tubing, and

in which the flow of cooling liquid through the tubing of the coil is so related to the flow of air transversing the coil, that the warmer air first encounters the cooler portions of the cooling unit.

5 Stated more particularly in reference to the assembly to be described, the improvements include a novel arrangement of air baffles so located within the path of air movement as uniformly to distribute and proportion the components of the stream of cooling air to and through the several bottle containing regions or compartments of the cabinets.

10 The arrangement of cooling coil, ducts, air impeller and parts of the cabinet are further objectively such as to obviate defrosting, and further such as to minimize interchange of room air and cooled air such as would otherwise occur through a service opening of the cabinet.

15 The foregoing and numerous other objects will more clearly appear from the following detailed description of a selected exemplary embodiment of the invention, particularly when considered in connection with the accompanying drawing, in which:

20 Fig. 1 is a view taken along staggered vertical planes longitudinally of the cabinet, certain parts being shown in section;

25 Fig. 2 is a sectional view as taken along vertically staggered horizontal planes through the cabinet assembly embodying present improvements; and

30 Fig. 3 is a vertical, transverse or fore and aft sectional view taken inwardly of one of the end walls of the cabinet, the sectional portions of Fig. 1 being located by line 1—1 of Fig. 3 and those identifying Fig. 2, by line 2—2 of Fig. 3.

35 Referring now by characters of reference to the drawing, the cabinet enclosure or box per se, may be of usual or conventional construction except for present internal features and includes a relatively long rear wall 10, a relatively long parallel front wall 11, and opposite end walls 12 and 13. A bottom 14 completes, with the top to be described, the enclosure of the box. The top enclosure is completed by an upper ledge 15 and an angle portion 16 which may be provided with glazed sliding doors 17, operating in guides 18, in any suitable or conventional manner.

40 The front, rear, end and bottom wall elements 50 of the cabinet, may be as is preferred, of double thickness to provide an insulation space 20. This may, if desired, consist of an air insulation space, or may as preferred, contain a fibrous or other thermal insulating material (not shown).

45 There is provided in the cabinet a cooling coil

compartment 21 preferably constituted and defined by a suitable metal enclosure, formed for example, of sheets 22, and is so arranged that the cooling compartment bridges the front and rear walls 10 and 11, and serves to contain a cooling element such as a coil, later to be described. A powered air impeller is exemplified by a propeller-type fan 23 driven as by an electric motor M, and is supported by a suitable bracket 24. The fan and motor assembly is preferably located in the upper portion of the cooling coil compartment, over and to which is connected an elbow 25 serving as an outlet throat, as will appear, for the discharge stream from fan 23. The elbow member 25 is tightly connected to an air supply duct 26, shown as being of rectangular section; three sides of which are defined as by sheet metal elements 27, but leaving open or provided with outlet openings (not indicated), the bottom portion of this duct. This may be, as is preferred, closed by a suitable wide mesh wire guard grill or the like, indicated at 30. Metal lath or the like has been found highly satisfactory for this purpose. It will be noted that the supply duct 26 opens downwardly into a reach-in space or compartment 31, defined by the back, top and front wall of the cabinet, and extending below and forwardly of the supply duct, the latter being located along the rear wall and preferably in the uppermost region of the cabinet, extending lengthwise thereof.

The lower portion of the box is, as shown, of substantially rectangular shaping and serves to contain the bottles B reposing in the cabinet for cooling purposes, and usually awaiting service to the trade. The bottle compartments proper may be considered to be of the height of the adjacent return air duct 32. Similarly to the duct 26, three sides of this portion of the return duct are constituted by usual sheet metal elements such as 33 and 34, and one side being open adjacent the bottles, the latter side being of a relatively open construction and guarded as by a large mesh screen, for example, a grill of metal lath 35 similar to the closure 30 of duct 26. The return air duct extends through the cabinet in a direction generally parallel to the supply duct, and the end of the return duct opposite wall 13, opens into the lower portion of the cooling coil compartment 21. It will now have appeared that there is set up what is virtually a closed path air circulating system, the direction of movement of the air stream therein being indicated by the arrows in the several figures of drawing.

It will be understood as not strictly essential that the cooling coil compartment be located at one end of the cabinet. In larger size units, two of the systems of supply and return ducts may be located so as to be supplied from and return air to a compartment such as 21, which in such case (not shown) would be located, for example, centrally of a longer or larger cabinet. Such an arrangement being essentially a duplication of structure thus far described, becomes evident without further description or illustration.

For the purpose of promoting uniformity of cooling effect in the different bottle containing regions of the cabinet, several further expedients have been devised and have been found by experience, virtually to assure uniform cooling of the bottles throughout the assembly. Such provisions include a series of graduated baffles each of which is shown as transversely bridging the duct 26; these are shown in section (Fig. 1) and one is indicated at 41, being the smallest baffle in area,

located most proximate the cooling coil to be described, and the fan 23, hence being of least area. Slightly and progressively larger baffles 42, 43, 44 and 45 are employed in spaced relation along the supply air duct. Each of these presents a downwardly curved air-deflecting surface (Fig. 1) and each of the baffles numbered 41 through 45 is located substantially centrally above a corresponding bottle compartment therebelow, the latter being designated at 46, 47, 48, 49 and 50 in the order of their remoteness from the cooling coil housing 21. These compartments may be considered as defined at one side by the grid or guard 35; at the opposite side or end by the rear wall 10, and laterally bounded by a series of transverse partitions each designated at 55; a plurality or some of these partitions are, by preference for best results, but not of strict necessity, extended upwardly above the bottle compartment proper, so as to provide baffles 56. These, for economy and convenience of production, are virtually extensions of the partitions 55 which thus are of varying heights and areas with the largest and highest thereof located most proximate the cooling coil compartment 21, as suggested by Fig. 1. It will appear that, as the velocity of flow through duct 26 decreases toward its most remote end, the successive baffles will serve in progressively greater degree, to deflect downwardly the streams of cooled air therefrom. Similarly, the progressively reduced baffles (in area from left to right, Fig. 1) will serve decreasingly to obviate "short circuiting" effects, and thus will tend to equalize the flow of air from the supply duct downwardly and across the compartment 31 and into the several bottle compartments, thence outwardly through the return duct 32. Experience in actual usage has borne out the effects noted, and has resulted in the present arrangement.

A further and advantageous feature of the air circulation agencies and the box construction, arises from the location of the supply duct and return duct respectively at top and bottom of the cabinet interior, and also adjacent opposite sides of the cabinet, whereby the air stream is compelled to traverse the box relatively completely, and to cover, without voids in the bottle stacks, all of the useful cooling space within the several bottle compartments.

A still further advantage has been arrived at by virtue of the arrangement of parts and the flow circuit described. It will best appear from Fig. 3, that a line connecting the centers of ducts 26 and 32 will substantially parallel the plane of the access opening identified as to location, with the sliding doors 17. From this it will now be understood that the relatively rapid movement of air across the reach-in or door opening, tends to minimize the heat losses which otherwise would occur through interchange of air between the interior and exterior of the box. The arrangement has been referred to as a balanced draft design, and its function is such that, due to velocity of air flow from supply to return duct, very little actual heat loss occurs through the reach-in opening. This is of importance not only as conducting to efficiency, since the doors are frequently open for great lengths of time during periods of active bottle service, but also tends toward still further uniformity of temperature of the bottles and contents as served.

A further distinct advantage in service usage of the arrangement described, will become apparent when it is considered that as is usual in commercial utilization of a cabinet of this type,

the partial depletion of bottles from the various compartments 46—53, necessitates replacement of the bottles therein, by relatively warmer bottles from cases, etc., and at room or higher temperature. It should be importantly noted that the makeup bottles will normally be added on top of those remaining in each compartment. It will now appear that such relatively warmer bottles are, by virtue of this arrangement, exposed to the cooler portions of the air stream 10 circulating through the cabinet, and thus will be relatively quickly chilled with marked advantage in service to the trade.

Referring now more particularly to a preferred form of cooling coil, and its makeup, assembly, and relation to the elements earlier described, the coil is generally indicated at 60 and consists of a plurality, shown as four, of superposed banks or groups 61, 62, 63 and 64. The tubing within each bank or group is of course continuous, and is formed into a series of turns from right to left (Fig. 1) and from end-to-end of the bank (Fig. 2), each bank being provided with end connections. The lowermost such bank 61 is supplied with a cooling or refrigerating liquid through a connection 65 (Fig. 2) and the uppermost bank is provided with the return or outlet connection 66, the banks being related in series from bottom to top of the assembly 60 within the cooling duct. It is contemplated that the unit 60 consist of an evaporator supplied, for example, from a suitable compressor-condenser-evaporator system, (not shown since not material to present improvements) it being, however, understood that coil 60 may be supplied with a cooling liquid such as brine, water or the like, from any suitable source.

Further to describe the makeup of coil 60, it will be observed from the comparison of Figs. 1 and 2 that, as viewed endwise, each of the banks appears substantially as in Fig. 1; as viewed side-wise, each such bank is of a generally oval shape characterized by rounded end turns and intervening horizontal, linear passes of tubing. In forming up each of the banks the tubing thereof is so arranged that its successive turns are spirally related, and further so that the upper linear pass of each turn is displaced in a horizontal direction, slightly from its companion linear pass in the same turn or convolution. From this it results that in the successive banks 61—64 in the order encountered by the air stream upwardly through compartment 24, the air stream is compelled to pursue a series of sinuous or zig-zag paths through the open spaces between successive convolutions of the series of vertically arranged banks. Each turn of tubing within each bank is located at a slight acute angle to an adjacent vertical plane, and hence is biased to the general path of air flow through the coil.

The speed of motor 24 and fan 23 is preferably so regulated in relation to the flow of refrigerant or cooling fluid through the coil 60, that, under normal conditions of usage and under average humidity conditions, there will occur no appreciable frost deposit on even the coldest of the banks of the cooling coil. This conduces to continuity of service and greatest efficiency, with minimization of the out-of-service periods usually incident to defrosting.

It will now have appeared that the improvements as described serve fully to attain each of the several objectives hereinabove expressly stated, and numerous others implied from the description of parts, arrangements and purposes. Although the invention has been described by

making explicit reference to a single selected embodiment, the detail of description is to be understood solely as illustrative and not as restrictive; inasmuch as many variants are possible within the intended scope of the claims hereunto appended.

I claim as my invention:

1. In a beverage cooling cabinet of dry, circulating air type, a box structure having a top angle opening, and closures providing, when open, for access to the interior of the box, an air supply duct in the uppermost portion of the box and back of said opening, a second duct substantially parallel to the first said duct, and located in the lowermost part of the box and adjacent the wall thereof opposite the first said duct, a cooling coil across which air is adapted to be passed in the course of circulation through the ducts and the interior of the box, a fan in the duct assembly for moving air therethrough and through the box, and partitions across the interior of box and in planes substantially at right angles to said ducts.

2. The combination and arrangement of elements as recited by claim 1, but further particularized in that the ducts and box are mutually so arranged as to create a flow of cooling air across and downwardly of the space within the box.

3. In a cooler for bottled beverages, a cabinet enclosure forming a space for the reception of bottles while being cooled for serving, an air supply duct to the bottle space, a return duct communicating with the bottle space, a cooling coil compartment connected between said ducts, and a cooling coil assembly in the last said compartment, the coil assembly comprising a plurality of superposed interconnected banks of cooling coils, each of said banks being of a generally oblong form as viewed in vertical planes and consisting of a number of oblong turns, spirally connected and related, and an impeller for moving air through the several said banks of coils and said ducts, and across the bottle compartments.

4. The combination and arrangement of elements as recited by claim 3 but further characterized in that each of the turns of tubing in each of the individual banks thereof, is located at a slight acute angle to the vertical, and to the path of the air stream impelled through the several banks of tubing.

5. The combination and arrangement of elements as recited by claim 3 but further characterized in that the several banks of tubing constituting the cooling coil assembly, are connected in series relation and are so disposed that a normally cooler portion of the coil assembly is first engaged by the relatively warmer current of air traversing the duct system and box.

6. In a bottle cooler cabinet assembly of dry air type, a cabinet of elongate top-open, reach-in type, a plurality of partitions coacting with the cabinet walls to define bottle spaces in the cabinet, the cabinet walls forming a compartment above the partitions through which the bottle spaces are accessible, a cooling unit and ducts in the cabinet including a supply duct extending lengthwise of the cabinet and in the upper portion of the said compartment, and a return duct leading from the lower portions of the several said bottle spaces, the ducts being located to be supplied with air from the cooling unit, an air impeller in the line of flow of air through the ducts and cooling unit, and a series of baffles in the line of flow of air through the top duct, each of said baffles being located to direct a stream of cooled air downward-

ly into, and substantially centrally of one of the bottle compartments.

7. In a beverage cooling cabinet for bottled products and the like, an elongate enclosure, a cooling coil compartment in the enclosure, a cooling coil therein, ducts extended along opposite walls of the enclosure, one in the upper portion thereof for supplying cooled air at various points along the space within the enclosure, and a second duct extended along an opposite wall and in the lower region of the enclosure, the ducts communicating with the cooling coil compartment, air impelling means serving said ducts and coil compartment, and a plurality of partitions defining bottle spaces within a lower portion of the enclosure, the partitions being of graduated height and area.

8. The combination and arrangement of elements as recited by claim 7 but further characterized in that the partition of greatest height and area is located nearer that end of the cooled air supply duct nearest the cooling coil compartment.

9. In a beverage cooler of circulating air type, a cabinet, a cooling coil, a compartment therefor in the cabinet, an air fan, a cooled air supply duct extending along one wall of the cabinet, a return duct in communication with the lower portions of the cabinet, bottle compartments provided adjacent the return duct, the supply duct being provided with air discharge openings, and a series of baffles spaced along the line of flow of the air supplied to the interior of the cabinet, each said baffle being located transversely to the line of such air flow, and above one of the bottle compartments.

10. The combination and arrangement of elements as recited by claim 9, but further characterized in that the said baffles are of graduated area, with the baffle of least area being located most proximate to the source of cooling air and the largest said baffle spaced most remotely from the source of cooled air, and in which each of the plurality of bottle compartments is substantially centralized with respect to an air stream directed thereto by one of said baffles.

11. In an air cooling assembly adapted for use in a beverage cooling cabinet or the like, a cooling coil compartment and a cooling coil assembly therein, a blower for moving air through the coil assembly, the coil assembly comprising a number of turns of tubing arranged in a series of banks, each of said banks consisting of a series of lengths of spirally wound tubing, the tubing in each bank being characterized in that each full turn thereof is sloped slightly with respect to the line of air flow in traversing the coil assembly and so arranged that a major length of the tubing in each bank extends primarily across an air stream to be cooled thereby, with corresponding tubes of the several

adjacent banks successively engaged by the air stream, relatively vertically staggered, the arrangement being such that the successively encountered banks of tubing present a horizontally staggered, vertically spaced succession of tubes encountered in turn by the air stream moving through the assembly.

12. In a beverage cooling box of air circulating type, adapted for the cooling of bottles of beverages or the like, an elongate insulated box or cabinet having a sloping surface along its forward upper margin, with said surface provided with an access opening, doors therefor, a cooling coil compartment transversely bridging opposite walls of the cabinet, cooling coils in said compartment, a fan in said compartment, a cooling air supply duct extended from said compartment and thence along an uppermost portion of the rear wall of the cabinet, the duct having openings directed downwardly into the cabinet, a return duct extended lengthwise of the cabinet and along the lowermost portion of a wall thereof opposite that adjacent the supply duct, the cooling coil compartment interconnecting said ducts, a plurality of banks of cooling coils in the compartment therefor, each bank composed of a series of helically arranged convolutions of tubing, the major portion of each said convolution lying in a plane at a slight angle to the vertical, and corresponding portions of the coils in adjacent banks as successively encountered by the air stream, being relatively horizontally staggered whereby to provide a zig-zag path of air moving through the several banks of coils, a plurality of baffles spaced along the cabinet and arranged transversely of the line of air flow through the air supply duct, said baffles being of graduated area with the smallest thereof most proximate to the coil compartment and fan, the lower portion of the box being provided with a series of transverse baffles, the baffles being spaced to provide bottle compartments therebetween, and being of graduated height and area, the partitions being staggered endwise of the box, in respect to said baffles, whereby the latter tend to direct individual air streams downwardly and substantially centrally of the bottle spaces provided by adjacent partitions.

LOUIS WEISS.
